Primary Examiner—Louis S. Zarfas
Assistant Examiner—Deanne Levy

(57) **CLAIM**

The ornamental design for a nestable crate for containers, as shown and described.

DESCRIPTION

FIG. 1 is a perspective view of the nestable crate for containers showing our new design;
 FIG. 2 is a top plan view thereof;
 FIG. 3 is a front elevational view thereof, the rear elevational view being a mirror image thereof;
 FIG. 4 is a left side elevational view thereof, the right side being a mirror image thereof;
 FIG. 5 is a bottom plan view thereof.
 The broken lines in FIGS. 1-5 forms no part of the claimed design.
